UNITED STATES PATENT OFFICE.

PAUL H. ZIMMER, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,102,315.

Specification of Letters Patent.

Patented July 7, 1914.

Application filed March 1, 1913, Serial No. 751,493. Renewed December 3, 1913. Serial No. 804,484.

To all whom it may concern:

Be it known that I, PAUL H. ZIMMER, a citizen of the United States, residing at Milwaukee, in the county of Milwaukee and State of Wisconsin, have invented new and useful Improvements in Motor-Controllers, of which the following is a full, clear, concise, and exact description, reference being had to the accompanying drawing, forming 10 a part of this specification.

My invention relates to motor controllers.

It has among its objects to provide a simple and easily manipulated compound starter which will insure full field strength 15 of the motor in starting; which will necessitate due regulation of the motor armature prior to regulation of the field, and which will stop the motor without varying its field strength.

20 Other objects and advantages of my invention will hereinafter appear.

For the purpose of fully and clearly disclosing the nature and advantages of my invention I shall describe the controller diagrammatically illustrated in the accompanying drawing, which embodies my invention in a preferred form. It should be understood, however, that the form of the controller selected for the purpose of illustration is not to be considered as unnecessarily limiting the scope of the appended claims.

The controller illustrated comprises two arms 1 and 2, the former being movable over a series of contacts 3 to vary a resistance R and the latter being movable over a series of contacts 4 to vary a resistance R'. The resistance R is shown as connected in circuit with the armature A of a shunt motor M while the resistance R' is shown connected in circuit with the shunt field F of said motor.

The arms 1 and 2 are movable together to the right to remove the resistance R from the armature circuit of the motor, where- 45 upon the arm 1 is held by a retaining mag-

net 5 against the action of a return spring 6. The arm 2 is then movable to the left independently of the arm 1 to insert the resistance R' in the field circuit of the motor. As is well understood in the art, the removal of the resistance R from the armature circuit of the motor accelerates the 50 motor to a predetermined degree, while the subsequent insertion of the field resistance 55 further accelerates the motor.

In controllers of the compound type it is desirable, if not imperative, to start the motor under full field strength, to remove the armature resistance prior to the insertion of any field resistance and to guard 60 against variation of the field strength in stopping the motor.

I shall now describe in detail the very simple construction illustrated which secures the aforesaid results and which further enables the complete operation of the controller by a single handle, and further, the removal of the field resistance and subsequent removal of the armature resistance by operation of said handle in a single direction. The arms 1 and 2 are preferably pivoted concentrically as illustrated, and the latter is employed as the operating arm. To this end the arm 1 is provided with an upwardly extending lug 7 to be engaged by the arm 2 in its movement to the right and said arm 2 is provided with a suitable operating handle 8. With this arrangement the arm 2 may be moved to the right to move the arm 1 into position to be held by the retaining magnet 5, whereupon said arm 2 is left free to be moved to the left independently of the arm 1. The arm 1 is returnable to initial position by the spring 6, which in practice is preferably a hub spring. The 75 arm 2 has a wider range of movement than the arm 1, which is limited by the magnet 5 and a stop 9 and said arm 2 moves over its contacts 4 only when outside of the range 80 of movement of the arm 1. When moved with the arm 1 the arm 2 engages a contact segment 10, through the medium of which it maintains the continuity of the field circuit during the removal of the armature resistance. As before set forth, the arm 1 85 is movable to the right to remove the resistance R while the arm 2 is movable in the same direction to remove the resistance R' and movable to the left to insert said resistance. 95

As illustrated, the arm 1 is in initial position and out of engagement with its contacts 3, thereby interrupting the armature circuit of the motor. The arm 2 is in a position to include a portion of the resistance 105 R' in the field circuit of the motor.

The operation of the controller and the circuit connections established thereby will now be described. To start the motor the handle 8 is moved to the right, thereby 110

first moving the arm 2 over its contacts to remove the field resistance R' from circuit. When the arm 2 reaches the segment 10 all of the field resistance R' will be removed 5 from circuit and said arm will engage the lug 7 on the arm 1. Continued movement of the arm 2 will then move the arm 1 into engagement with its contact 3. This completes the motor circuit. The field circuit 10 of the motor may be traced from line L by conductor 11 to the hubs of both arms 1 and 2, thence through arm 2 to segment 10, by conductor 12 through the shunt field winding F to the line L' . The armature circuit 15 may be traced from conductor 11 through arm 1 to the first of its contacts 3, thence through all of the resistance R, by conductor 13 through the motor armature A to line L' . The motor is thus started with full field 20 strength and with all of the resistance R in circuit with its armature. Continued movement of the two arms to the right will gradually remove the resistance R without affecting the field circuit. When all of the resistance R is removed from circuit the arm 25 1 is grasped by the retaining magnet 5. The retaining magnet is shown as connected directly across the lines by conductors 14 and 15 through a resistance 16. The arm 2 is 30 then free to be moved to the left and, upon passing off of segment 10 and onto its contacts 4, will gradually insert the resistance R' in circuit with the shunt field winding F. The arm 2 is unbiased, and accordingly may 35 be left in any desired position in accordance with the degree of field regulation desired. It will thus be seen that the controller insures the removal of all field resistance prior to starting the motor and also insures the removal of all of the armature resistance 40 prior to the insertion of any of the field resistance. To stop the motor the arm 1 is released from the magnet 5, whereupon it is returned to initial position by its spring 6, thereby gradually reinserting the resistance R in the armature circuit and then interrupting the armature circuit. If, during operation of the motor the arm 2 is moved to 45 insert resistance in the field circuit, it will be out of the range of the arm 1 and accordingly will be unaffected by the return of the arm 1 to initial position to stop the motor. Consequently the field strength of the motor will in no wise be varied by the controller 50 upon operation thereof to stop the motor. Any field resistance previously inserted in circuit will remain in circuit until the arm 2 is manually operated to remove the same.

What I claim as new and desire to secure 60 by Letters Patent is:

1. A motor controller provided with an armature controlling member, and a field controlling member, the latter in its operative positions being out of the range of 65 movement of the former and being movable

in a single direction to successively return to initial position and engage and move said former member away from its initial position.

2. A motor controller provided with an armature controlling member and a field controlling member, said field controlling member being movable in one direction from its initial position to engage and move said armature controlling member for starting 75 and in an opposite direction from its initial position for field control.

3. In a motor controller, in combination, a field resistance, an armature resistance, and two controlling elements movable in the 80 same direction one by the other to remove said resistances successively, said field resistance controlling element being then movable in a reverse direction to regulate said field resistance and when so operated being 85 independent of the return movement of said armature controlling element.

4. In a motor controller, in combination, an armature controlling member biased to initial position, means for retaining the same 90 in running position, a field controlling member movable in a single direction to increase the field strength of the motor and then engage and move said armature controlling member from initial position to running position, said field controlling member being thereafter movable to a position to weaken the motor field and to be independent of the return movement of said armature controlling member. 95

5. In a motor controller, in combination, a series of field resistance contacts, a series of armature resistance contacts, said series of contacts extending in opposite directions, a controlling member movable over said 100 armature resistance contacts, a member movable over said field resistance contacts and also movable to engage and operate said armature resistance controlling member, said members removing their respective resistances upon movement in the same direction. 110

6. In a motor controller, in combination, an armature resistance, a field resistance, two oppositely extending series of contacts connected to said resistances, two members movable in the same direction over said contacts to remove said resistances, and means operatively connecting said members when in their respective initial positions for enabling operation of said armature resistance controlling member by said field resistance controlling member, said field resistance controlling member when in engagement with its respective contacts being unaffected by the return movement of said armature resistance controlling member to its initial position. 115

7. In a controller for electric motors, in combination, two concentrically pivoted con- 120

130

trolling members, two series of contacts engaged thereby respectively, resistances connected to said series of contacts to be removed from circuit by movement of said members in the same direction, one member when disengaged from its series of contacts engaging and operating the other member and being thereafter returnable to its contacts independently of the other member

and being unaffected by the return movement thereof.

In witness whereof, I have hereunto subscribed my name in the presence of two witnesses.

PAUL H. ZIMMER.
